UNITED STATES PATENT OFFICE.

WILLIAM E. SPARKS, OF NEW BRITAIN, CONNECTICUT, ASSIGNOR TO P. & F. CORBIN, OF SAME PLACE.

DOOR-CHECK.

SPECIFICATION forming part of Letters Patent No. 255,893, dated April 4, 1882.

Application filed February 15, 1882. (No model.)

To all whom it may concern:

Be it known that I, WILLIAM E. SPARKS, of New Britain, in the county of Hartford and State of Connecticut, have invented certain 5 new and useful Improvements in Chain Fasteners for Doors, of which the following is a specification.

My invention relates to chain fasteners for doors in which a base having a notch in its 10 edge at one side is provided with a pivoted disk or button having link-receiving recesses which, when the button is in a certain position, coincide with the notch in the base, so that a ring or chain-link may be inserted 15 in the link-receiving recesses when said recesses are opposite said notch and retained therein by partially rotating the disk; and the objects of my invention are to provide a secure, cheap, and convenient chain fastening 20 for doors. I attain these objects by the mechanism illustrated in the accompanying drawings, in which—

Figure 1 is a front elevation. Figs. 2 and 3 are side elevations. Fig. 4 is a horizontal 25 section on line $\alpha\alpha$ of Fig. 3. Fig. 5 is a perspective view of the base-plate; and Fig. 6, a perspective view of the button, showing its rear side.

A designates a plate to which a staple and 30 chain, B, is permanently secured in any ordinary manner.

C designates a base-plate, and D a button pivoted thereto, and to which plate and button the opposite end of the chain may be attached and detached in the manner hereinafter described, the same being designed for use 35 by securing one plate upon a door-casing and the other upon a door in such manner as to allow the door, when the chain is attached to 40 both plates, to be partly opened, but secured against being fully opened, as in other chain fastenings. The novelty of my invention consists in the means for and manner of fastening and unfastening the free end of the chain— 45 that is, the end which is not permanently secured to either plate.

The base-plate C is provided with a notch, α , in its edge and upon one side, as shown,

while the portion of its face which is covered by the button D is substantially flat. This 50 notch is made of a sufficient width to receive the end link, b, upon the free end of the chain. The button D is substantially in disk form, but is somewhat hollowed out upon its back, as shown in Figs. 4 and 6, and it is pivoted to the plate C, so that it may rotate thereon. In order to prevent it from turning too freely, I place a friction-spring, c, Figs. 3 and 4, around its pivot. 5

Upon one side of the button there is a rib, d, which serves as an operating-handle and also as a stud or hook to take into the end link, b. By the sides of this rib at the edge of the button there are two link-receiving recesses, e e, Figs. 3 and 6, to admit of the end 65 link, b, being slipped over and upon the rib d. When the recesses e e of the button D are brought to coincide with the notch α in the base-plate by turning the button on its pivot the end link may be passed endwise into the 70 notch α and back of the rib d. It may then be brought over and upon said rib and entirely forward of the base-plate. By then turning the button the rib and end link are carried over the solid portion of the base-plate—that 75 is, away from in front of the notch α —so that the chain is securely held thereto, as shown in Figs. 1 and 2, and cannot be detached therefrom except by turning the button to bring the rib and recesses in front of the notch α . 80 This notch is made upon one side, so that the weight of the chain will have a tendency to prevent the button from accidentally working into the proper position for unfastening the chain. 85

I claim as my invention—

In a chain fastener, the combination of the base having the notch α at one edge and the rotating button pivoted thereto having the link-receiving recesses and holding-rib, substantially as described, and for the purpose specified. 90

WILLIAM E. SPARKS.
